UNITED STATES PATENT OFFICE

1,975,911

ROTARY BLOWER IMPELLER

Willem van Rijswijk, Baden, Switzerland, assignor to Aktiengesellschaft Brown Boveri & Cie., Baden, Switzerland, a joint-stock company of Switzerland

Application February 23, 1932, Serial No. 594,458
In Germany February 23, 1931

9 Claims. (Cl. 170—173)

This invention relates to improvements in rotary blowers or compressors and more particularly to an improved construction in the rotating member or impeller wheel for such blowers or 5 compressors.

When the impeller wheels of rotary blowers or compressors are provided with blades extending in a substantially radial direction relative to the shaft on which such wheels are mounted, the 10 blades and the hub of the wheels may be made integral or the blades may be secured to the hub by any suitable type of fastening. In cases where the wheels must be very light, the blades must be relatively thin. Such blades are, however, subjected to very high stresses in the circumferential 15 direction when the speed of the wheel is either accelerated or retarded and may be easily caused to oscillate which causes breaking of the blades due to fatigue of the material of which the blades 20 are constructed.

It is, therefore, among the objects of the present invention to provide an impeller wheel construction for rotary blowers or compressors in which the weight of the wheel is reduced by 25 constructing the blades of sheet metal secured to the hub.

Another object of the invention is to provide an impeller wheel construction for rotary blowers or compressors in which the blades are constructed of sheet metal and are individually secured to the hub.

Another object of the invention is to provide an impeller wheel for rotary blowers or compressors in which the several blades are constructed of several joined sheet metal portions 35 individually secured to the hub.

Another object of the invention is to provide an impeller wheel construction for rotary blowers or compressors in which the blades are constructed of several sheet metal portions individually so secured to the hub as to avoid diminishing the material at the periphery of the hub and hence the circumferential strength of the hub.

45 Objects and advantages other than those above set forth will be apparent from the following description when read in connection with the accompanying drawing in which:

50 Fig. 1 illustrates one embodiment of the invention in which a portion of the shaft and of an impeller wheel of a rotary blower or compressor are shown, with only a few blades secured therein, in a view taken along the longitudinal axis of the shaft;

Fig. 2 is an illustration of the view shown in Fig. 1 taken at right angles to the shaft;

Fig. 3 is a modified embodiment of the invention in a view similar to that shown in Fig. 1 but showing a different form of blade root or 60 fastening with the hub forming a portion of the wheel;

Fig. 4 is a view of the illustration shown in Fig. 3 taken at right angles to the shaft;

Fig. 5 is a view similar to that shown in Figs. 65 1 and 3 of a modified embodiment of the invention in which one edge of one of the portions forming the blades extends beyond the side of the hub and is curved to form a guide for the medium 70 upon which the blower operates;

Fig. 6 is a view similar to that shown in Fig. 5 of a modified embodiment in which each of the portions forming one blade have an edge thereof 75 extending beyond the hub, which edges are curved to form a guide for the medium on which the blower operates and are joined at the outer edge thereof;

Fig. 7 is a top view of the embodiment shown in Fig. 5, taken on line 7—7 of Fig. 5; and

Fig. 8 is a top view of the embodiment shown 80 in Fig. 6, taken on line 8—8 of Fig. 6.

Referring more particularly to the drawing by characters of reference, the reference numeral 11 designates a portion of a shaft on which any desired number of impeller wheels are to be mounted in a suitable manner. Each of the impeller wheels comprises a hub 12 and a plurality of blades formed of separate sheet metal portions 13 and 14 extending in such manner that the blades extend substantially radially from the hub 90 relative to the shaft 11. The portions forming each blade are attached to each other by some suitable means such as welding or riveting and each of the blade portions is individually secured to the hub by means of a root member as shown at 16 and 17 in Fig. 1 or at 18 and 19 in Fig. 3. The root members are in the form either of rod-like portions which fit in close engagement into grooves in the hub or of quadrangular portions forming, with similarly shaped grooves in 100 the hub, dove-tailed joints by which the blade portions are retained in the hub. The root members may, of course, be secured into the grooves by welding if desired. It will be seen in Fig. 1 that the root members 16 are on a different circle, relative to the axis of the shaft 11, from the circle on which the root members 17 are located. The material removed from the hub to form the grooves which receive the root members 105 is thus removed substantially uniformly through- 110

out the entire mass of the hub and the tensile strength of the hub remains constant throughout all portions thereof. Each of the blade portions, being at the same angle with the periphery of the hub, is stressed by the same amount and the complete blade is very rigid as respects bending on an axis at right angles to the axis of the shaft. The several blade portions may thus be made very light whereby the likelihood of oscillations due to the low inertia of the blades and their corresponding high frequency is very much reduced.

When a relatively small number of blades are to be arranged on each hub, the several portions forming each blade may be formed with the quadrangular root portions 13 and 19 engaging in similar quadrangular grooves formed in the periphery of the hub 12 in such manner as to form a dove-tailed joint. The grooves are all at the same depth from the periphery of the hub and the portions 13 and 14 are all of the same length and the portions forming each blade are joined. It will be seen, considering center lines taken radially of the hubs through the grooves, that the spacing of the blade roots in the embodiment shown in Fig. 3 is the same or greater than the spacing of the blade roots shown in Fig. 1. The amount of material remaining in the periphery of the hub is therefore sufficient to prevent overstressing thereof. The number of blades which may be mounted on the hubs of same size by the different types of mountings above described is, however, less in the form shown in Fig. 3 than in the form shown in Fig. 1 due to the requirement for sufficient tensile strength in the hub at the periphery thereof.

Under some conditions of operations, it is desirable to provide the blades with an inlet lip or edge which will aid in guiding the air or other medium operated upon by the blower into the blades. Figs. 5 and 7 illustrate one embodiment of the invention in which only the blade portion 14 which is directly in contact with the medium handled by the blower is provided with the lip or guiding edge 21. The guiding edge is curved on the most desirable curve to secure the maximum delivery of air to the front of the blade portion 14. The guiding edge need not extend over the full length of the blade but may be restricted to the length of the blade over which the gas is actually entering. To secure the maximum rigidity of the blades, and particularly of the inlet or guiding edges thereof, it is preferable that the rear portion 13 of each blade be also extended beyond the hub as indicated at 22 and be curved in such manner as to be capable of joining with the guiding edge 21 to form a reinforced guiding edge for the entire blade.

The present invention provides a blade construction for rotary blowers or compressors in which the several portions forming each blade reinforce each other and avoid the production of excessive stresses in the blade upon change in speed of the blower. Oscillations of the blade are also very much reduced by the present construction thus avoiding breakage of the blades due to fatigue.

Although but a few embodiments of the present invention have been illustrated and described, it will be apparent to those skilled in the art that various changes and modifications may be made

therein without departing from the spirit of the invention or from the scope of the appended claims.

It is claimed and desired to secure by Letters Patent:

1. An impeller wheel for rotary blowers or compressors comprising a hub, and a plurality of blades extending therefrom, each of said blades being formed from two portions joined along an edge thereof and being attached to said hub. 80

2. An impeller wheel for rotary blowers or compressors comprising a hub, and a plurality of blades extending in a substantially radial direction therefrom, each of said blades being formed from two portions joined along an edge thereof and being secured to said hub, the blade portions being substantially straight. 90

3. An impeller wheel for rotary blowers or compressors comprising a hub, and a plurality of blades extending therefrom, each of said blades being formed from two portions immovably joined along an edge thereof and being individually attached to said hub. 95

4. An impeller wheel for rotary blowers or compressors comprising a hub, and a plurality of blades extending therefrom, each of said blades being formed from two portions joined along an edge thereof and extending to equal depths into said hub for attachment thereto. 100

5. An impeller wheel for rotary blowers or compressors comprising a hub, and a plurality of blades extending therefrom, each of said blades being formed from two portions joined along an edge thereof and extending to unequal depths into said hub for attachment thereto. 105

6. An impeller wheel for rotary blowers or compressors comprising a hub, and a plurality of blades extending therefrom, each of said blades being formed from two portions joined along an edge thereof and being attached to said hub, one of the blade portions having an edge thereof extending beyond an edge of said hub to form a guide for a medium to be operated on by the blower. 115

7. An impeller wheel for rotary blowers or compressors comprising a hub, and a plurality of blades extending therefrom, each of said blades being formed from two portions joined along an edge thereof and being attached to said hub, the blade portions having joined edges extending beyond an edge of said hub to form a guide for a medium to be operated on by the blower. 120

8. An impeller wheel for rotary blowers or compressors comprising a hub, and a plurality of blades extending therefrom, each of said blades being formed from two portions immovably joined along an edge thereof and extending to unequal depths into said hub for individual attachment thereto. 130

9. An impeller wheel for rotary blowers or compressors comprising a hub, and a plurality of blades extending therefrom, each of said blades being formed from two portions immovably joined along an edge thereof and extending to unequal depths into said hub for individual attachment thereto, the blade portions having joined edges extending beyond the edge of said hub to form a guide for a medium to be compressed by the blower. 135
